DEVICE FOR TRANSMISSION OF ELECTRIC POWER WITH LARGE FREQUENCY RANGE

Gosta Allan Evert Mattsson, Spanga, Sweden, assignor to Telefonaktiebolaget L M Ericsson, Stockholm, Sweden, a corporation of Sweden

Application February 17, 1955, Serial No. 488,953

Claims priority, application Sweden February 22, 1954

2 Claims. (Cl. 333—96)

The present invention relates to a device for transmitting electric power with large frequency range.

A device according to the invention comprises a coaxial cable and is characterized by the inner conductor of the coaxial cable being divided into a number of sections arranged concentrically in succession and connected to each other by means of condensers.

Another characteristic feature of a device according to the invention is that the length S of the said sections, measured in kilometers, and the capacitance C of the two condensers, measured in farads, satisfy the relation

$$C = \frac{4 \times l}{r^2 \times S}$$

where l is the inductance of the coaxial cable, measured in henry/km., and r is the resistance of the coaxial conductor, measured in ohm/km.

A further characteristic feature is that the inner conductor of the coaxial cable is tubular.

The invention will be described more closely in relation to the accompanying drawing, in which Fig. 1 is a schematic view of a device according to the invention and Fig 2 shows one of the sections of the coaxial cable comprised in a device according to Fig. 1.

In the device according to Fig. 1, 1 is the outer conductor of a coaxial cable, the inner conductor of which is divided into a number of sections 21, 22, 23 . . . , arranged concentrically and connected to each other by means of condensers 31, 33 . . . .

The length S of each one of the sections 21, 22, 23 . . . , measured in kilometers, is chosen in such a manner in relation to the capacitance C of the condensers 31, 32 . . . , measured in farads, that these magnitudes satisfy the relation

$$C = \frac{4 \times l}{r^2 \times S}$$

in which l is the inductance of the coaxial cable, measured in henry/km., and r is the resistance of the coaxial cable, measured in ohm/km.

As appears from Fig. 1 the inner conductor of the coaxial cable, i.e. the sections 21, 22, 23 . . . , is tubular, which has proved especially suitable for this kind of device.

In Fig. 2 a suitable shape for a section comprised in a device according to Fig. 1, is shown. The outer and 60 inner conductors of the coaxial cables are referred to as

2

1 and 22, respectively. To obtain a good stability the inner conductor 22, which is made of copper, silver or another conducting material, is applied onto an inner supporting material 3 and insulated from said supporting material by means of an insulating layer 4. To fix the inner conductor relatively the outer conductor there are at suitable intervals a number of spacers 5 of some insulating material. The space between the inner and the outer conductor is filled with suitable di-electric material, such as air or some other gas.

It is naturally also possible to make a coaxial cable without the inner supporting material and with some kind of thermoplastic substance instead, such as polyethylene, polystyrol etc., either homogeneous or mixed with air or some other gas to form a foamy material.

A considerable advantage of a capacitively series loaded coaxial cable with tubular inner conductor is, that its characteristic impedance, the image impedance, has a very simple form, since it is possible to compare its characteristic for a very large frequency range with a resistance in series with a condenser. This entails, that if the cable is terminated by such a simple two-pole network, its working properties become equal to its image properties, independent of the length of the cable.

25 The capacitive series impedances may at the amplifying stages usually be included in the connecting condensers of the amplifier, as well on the input as on the output side, whereby the capacitance should be equal to the double value of the capacitance of the other condensers of the coaxial cable.

30 As example of the dimensioning of the condensers comprised in a coaxial cable the following figures may be mentioned: At a distance S=1 km. between the condensers their capacitance C for a certain cable type should be 1.0 μ f.; at S=3.5 km., C should be 0.3 μ f.

I claim:

1. A coaxial cable for transmitting electric energy having a wide frequency band, said cable comprising a tubular outer conductor continuous for the length of the cable, 40 and a coaxially disposed inner conductor, said inner conductor being in form of alternately disposed conductive sections and capacitance means all connected in series, the length of said conductive sections and the capacitance of said capacitance means being in accordance with the equation:

$$C = \frac{4 \times l}{r^2 \times S}$$

50 wherein S is the length in kilometers, C the capacitance in farads, l the inductance of the cable in henry/km. and r the resistance of the cable measured in ohm/km.

2. A coaxial cable according to claim 1 wherein said inner conductor is composed of alternately disposed tubular conductive sections all connected in series with the capacitance means.
